CLAIM

The ornamental design for a cupholder, as shown and described.

DESCRIPTION

FIG. 1 is a perspective view of a cupholder embodying my design;

FIG. 2 is a front elevational view thereof;

FIG. 3 is a left side elevational view thereof, the right side elevational view being a mirror image thereof;

FIG. 4 is a rear elevational view thereof;

FIG. 5 is a top plan view thereof;

FIG. 6 is a bottom plan view thereof;

FIG. 7 is a front elevational view of a second embodiment thereof;

FIG. 8 is a top plan view thereof; and,

FIG. 9 is a bottom view thereof.
